UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,926, dated December 6, 1887.

Application filed October 15, 1887. Serial No. 252,506. Term of patent 3½ years.

To all whom it may concern:

Be it known that I, ELLEN MORAN, of the city, county, and State of New York, have invented and produced a new and original 5 Design for a Pattern of a Lady's Costume; and I do hereby declare that the engraved prints accompanying this specification convey to any one accustomed to using paper patterns a clear understanding of how a garment made up by 10 the pattern will appear.

The design shows a basque and a round walking-skirt. The skirt displays a long front drapery that exhibits two groups of plaits at the right side turning and flaring toward each 15 other, is plain at the center of the front, and forms a yoke section that crosses the top of the panel and left-side gore, and a full deep back drapery that displays bournous loops and kilt-plaits at the top, and extends to the 20 edge of the skirt at the left side and several inches from the edge at the right side. The basque displays close-fitting fronts that exhibit a closing down the center, and shape two points below the closing; a close-fitting back that falls in two narrow tabs at the center and in a point at either side of the tabs; a standing collar, and coat-sleeves that exhibit long V-puffs that display side plaits flaring from the point more than half-way to the top, downward-turning plaits in the side edges 25 near the top, and a gathering across the top.

What I claim as my invention, and desire to secure by Letters Patent, is—

The design for a lady's costume, as shown in the engraved prints accompanying this 35 specification.

ELLEN MORAN.
